UNITED STATES PATENT OFFICE.

ROSE SMITH, OF CLEVELAND, OHIO.

WATER-HEATER.

SPECIFICATION forming part of Letters Patent No. 668,229, dated February 19, 1901.

Application filed September 4, 1900. Serial No. 28,964. (No model.)

To all whom it may concern:

Be it known that I, ROSE SMITH, a citizen of the United States, residing at Cleveland, in the county of Cuyahoga and State of Ohio, have 5 invented a new and useful Water-Heater, of which the following is a specification.

The invention relates to improvements in water-heaters.

One object of the present invention is to 10 improve the construction of water-heaters and to provide a simple and comparatively inexpensive device adapted to be readily applied to a furnace, range, or analogous heating apparatus to enable water to be heated 15 by gas for supplying boilers, bath-rooms, and the like with a supply of hot water.

Another object of the invention is to provide a water-heater which will be capable of 20 adjustment to arrange it to suit the size of the furnace or other heating apparatus to 25 which it is to be applied and to permit the jet pipe or tube to be arranged properly with relation to the water-pipe to secure the maximum effect upon the quantity of gas consumed.

The invention consists in the construction and novel combination and arrangement of parts hereinafter fully described, illustrated in the accompanying drawings, and pointed 30 out in the claims hereto appended.

In the drawings, Figure 1 is a vertical sectional view of a furnace provided with a water-heater constructed in accordance with this 35 invention. Fig. 2 is a transverse view of the water-heater. Fig. 3 is a detail perspective view of a portion of the hood.

Similar numerals of reference indicate corresponding parts in all the figures of the drawings.

40 1 designates a water-pipe designed to extend horizontally through the upper portion of a stove or a furnace 2 or other complete heating apparatus, as clearly illustrated in Fig. 1 of the accompanying drawings, and beneath the water-pipe is arranged a burner or jet-pipe 3, having a series of perforations located at intervals beneath the water-pipe and adapted to direct the flame against and around the same. The burner and the water- 45 pipe are arranged within a hood or casing consisting of an adjustable bottom 4 and an adjustable top 5. The adjustable bottom 4

is preferably composed of three sections—namely, a central section 6 and end sections 7. The central section 6 is provided at its 55 upper face with longitudinal ribs or flanges 8, having grooves 9 at their inner faces for the reception of the side edges of the end sections 7, whereby the latter are slidably connected with the central section. The end 60 sections, which are preferably reinforced by ribs, are provided with threaded apertures surrounded by bosses and receiving clamping-screws 10, which engage the upper face of the central section to secure the said sections in their adjusted position. The adjustable bottom, which is adapted to be introduced into a furnace through the door thereof, is extended until its ends contact with the opposite sides of the furnace, and it 65 is adapted to be supported in the enlarged or bulged portion of an ordinary furnace by simply resting against the walls thereof; but any suitable means may be employed for mounting the hood or casing within a furnace or other heating apparatus which does 70 not form a natural support for the hood or casing. The water-heater is designed for use in summer, when it is undesirable to use the furnace or heating apparatus, and it is 75 adapted to be placed in the latter as soon as it becomes too warm to use the same, and it may be quickly removed therefrom in the fall, when it becomes desirable to again use the furnace, and the change may be readily made 80 without employing a plumber or other skilled mechanic.

The top 5 of the hood or casing is composed of two sections 10 and 11, which are successively placed within the furnace after the bottom has been introduced therein and which are capable of longitudinal adjustment on each other. Each of the sections of the top 5 consists of a rear wall 12, an end wall 13, a top wall 14, and a front end portion 15, and 90 the end wall 13 is provided with an opening or slot 16 to enable the section to straddle the water-pipe and rest upon the bottom. The front portion 15 and the rear wall are provided at their lower edges with tapering recesses 17, forming scalloped edges and providing openings or apertures for the passage of air to supply the necessary draft to insure 95 proper combustion. The top walls 14 of the 100

sections are provided with longitudinal slots 18, which permit the escape of hot air and the products of combustion. The top sections 10 and 11 are open at the front between the ends 14 and 15 to afford access to the interior of the hood or casing, and the front of the latter is designed to be normally closed by two plates 19 of galvanized iron or other suitable material. These plates or cases are slid- 10 ily connected and are adapted to be adjusted longitudinally to enable them to be arranged to suit the sections of the top and to facilitate their introduction into the furnace. After the doors or plates 19 have been placed 15 in position they may be readily tilted forward toward the door of the furnace to open the hood or casing without entirely removing them therefrom.

The central section of the bottom is provided with a central opening 20, and it has a pair of slots 21, located at opposite sides of the opening and extending rearward from the front edge of the central section, as clearly illustrated in Fig. 3 of the accompanying 25 drawings. The burner preferably consists of the horizontal perforated jet-tube arranged within a T-shaped coupling 22, which is centrally located and from which depends a short pipe 23, and the latter extends through the opening 20, as clearly illustrated in Fig. 2 of the accompanying drawings. A tube 24 is connected at its upper end with the lower terminal of the pipe 23 and extends downward to approximately the bottom of the furnace 35 and is designed to have its lower end connected with a gas-pipe by means of a flexible tube. (Not shown.) The flexible tube, which may be readily connected with the lower end of the tube 24, is designed to extend to an 40 ordinary gas-burner, by means of which the supply of gas may be readily controlled.

The burner is supported by a bracket 25, approximately U-shaped, as clearly illustrated in Fig. 1, and provided with substantially L-shaped sides 26, arranged in the slots 21 and having their horizontal portions located beneath the burner and forming opposite supports for the same. The bracket is provided at its bottom with a smooth opening 27, surrounded by a depending annular flange and receiving the smooth portion of a bolt 28, which engages a threaded aperture 29 of the bottom of a hood or casing. The threaded aperture of the bottom of the hood or casing 55 is also preferably provided with an annular flange, and it will be apparent that by rotating the adjusting-screw the bracket may be raised and lowered to position the burner properly with relation to the water-pipe, so 60 that a maximum effect of the gas consumed may be had. The vertical adjustment of the burner does not affect the tube or pipe 24, which is much smaller than the depending branch or pipe of the burner and which rests 65 upon the bottom of the furnace. By having the tube 24 of less diameter than the depend-

ing branch of the burner air is admitted at the base of the burner for supporting combustion and the burner is permitted to be adjusted freely, and the said tube 24 never 70 becomes heated and will not injure the flexible supply pipe or tube which will be connected to its lower end. The water-heater by being arranged as shown is not affected by the wind, it does not give off any fumes, 75 and the draft through the furnace will draw off the fumes and gases given off by a range in cooking. Also the loose joint or connection between the tube 24 and the burner enables the parts to be readily assembled and 80 separated.

It will be seen that the water-heater is exceedingly simple and comparatively inexpensive in construction, that it is adapted to be readily applied to furnaces, ranges, and 85 analogous heating apparatus while the same are unemployed, and that the water-heater may be readily removed when it is desired to use the furnace or range to which it is applied. It will also be apparent that the hood 90 or casing is adjustable and that it is adapted to confine the heat and concentrate the same around a water-pipe, so that a maximum effect may be had from a quantity of gas, and that the gas-burner or jet-tube may be readily 95 adjusted to position it properly with relation to the water-pipe.

I desire it to be understood that various changes in the form, proportion, and minor details of construction such as are necessary 100 to adapt the water-heater to the character of furnace or other heating apparatus to which it is to be applied may be resorted to without departing from the spirit or sacrificing any of the advantages of the invention. 105

What I claim is—

1. In a device of the class described, the combination with a complete heating apparatus having a horizontal water-pipe, of a removable casing arranged within the heating 110 apparatus and extending over the water-pipe and forming a hood for confining heat around the said water-pipe, and a burner located beneath the water-pipe and carried by the casing, said casing being adapted to be taken 115 out of the heating apparatus to permit the latter to be used, substantially as described.

2. In a device of the class described, the combination with a complete heating apparatus having a water-pipe, of a removable extensible casing capable of adjustment to fit the heating apparatus and forming a hood around the water-pipe, and a removable burner arranged within the casing, substantially as described. 125

3. In a device of the class described, the combination with a complete heating apparatus having a water-pipe, of a removable casing comprising a bottom having extensible sections, and a top composed of extensible 130 sections and provided with openings to receive the water-pipe, and a removable burner

- arranged within the casing, substantially as described.
4. In a device of the class described, the combination with a complete heating apparatus, of a removable casing arranged within the heating apparatus and forming a hood around the water-pipe thereof and comprising a top and bottom having extensible sections, each top section consisting of a top wall, a rear wall, an end wall having an opening for the water-pipe and a front portion, a door arranged at the front of the casing and a removable burner located within the casing, substantially as described.
- 15 5. In a device of the class described, the combination with a complete heating apparatus provided with a water-pipe, of a casing surrounding the water-pipe and removably fitted in the heating apparatus, a vertically-adjustable bracket mounted on the casing and extending into the same, and a burner supported by the bracket, substantially as described.
- 25 6. In a device of the class described, the combination with a complete heating apparatus having a water-pipe, of a casing surrounding the water-pipe and forming a hood and removably fitted in the heating apparatus, said casing being provided at its bottom with slots, a vertically-adjustable bracket provided with approximately L-shaped sides arranged in the said slots, and a burner supported by the sides of the bracket, substantially as described.
- 35 7. In a device of the class described, the combination of a complete heating apparatus having a horizontal water-pipe, a casing detachably fitting within the apparatus and extending over the horizontal water-pipe and forming a hood for confining heat around the same, a burner located within and carried by the casing, an adjustable bracket supporting the burner and adapted to permit the latter to be moved to and from the water-pipe, said casing, burner and bracket being adapted to be readily removed from the heating appara-

tus to permit the latter to be operated, substantially as described.

8. In a device of the class described, the combination with a complete heating apparatus having a water-pipe, of a casing arranged within the heating apparatus and forming a hood for the water-pipe and provided at its bottom with an opening, said casing being also provided at opposite sides of the opening with slots, a bracket extending through the slots of the casing, an adjusting device connecting the bracket and the casing, a removable burner supported by the bracket and provided with a pipe extending downward through the said opening, and a tube extending from the pipe of the burner to the lower portion of the heating apparatus and adapted to be connected with a supply-pipe, substantially as described.

9. In a device of the class described, the combination of a casing comprising a bottom consisting of a central section having ways and end sections slidingly fitted in the said ways and adapted to be extended, and a top composed of sections, each section consisting of top, back and end walls and provided with a front portion, and a removable burner arranged within the casing, substantially as described.

10. In a device of the class described, the combination of a casing adapted to be arranged within a complete heating apparatus and composed of a bottom having extensible sections, and a top also composed of extensible sections and provided at the top walls with openings and having recesses at the lower edges of the walls, and a removable burner arranged within the casing, substantially as described.

In testimony that I claim the foregoing as my own I have hereto affixed my signature in the presence of two witnesses.

ROSE SMITH.
